UNITED STATES PATENT OFFICE

ARTHUR C. NELSON, OF ALEXANDRIA, MINNESOTA

PUMP

Application filed August 28, 1930. Serial No. 478,426.

This invention relates to the well pump which forms the subject matter of my application filed April 19, 1928, Serially Numbered 271,211 and allowed August 7, 1930, and which comprises a solid piston, means located below the piston and adapted to anchor it in a well, a cylinder slidably engaging the piston and provided near its upper end with a valve controlled intake port, a reciprocating discharge line having its lower end connected to and communicating with the upper end of the cylinder, and means adapted to limit the movement of the cylinder in a direction permitting its separation from the piston.

The present invention has for one of its objects to improve and simplify the general construction of the pump, and to attain this end comprehends the employment of a tubular piston so as to enable the fluid to be drawn therethrough into the cylinder and thus obviate the necessity of providing the cylinder with a valved intake port.

The invention further comprehends the employment of piston anchoring means which shall include a tube arranged in communication with the piston and provided with a valve controlled intake port.

The invention further comprehends the employment of a cylinder so constructed as to permit the washing out of any sand and sediment accumulating on top of the piston whereby to prevent the pump from sanding-up.

The invention still further comprehends the employment of piston anchoring means which shall be adapted to permit the piston to be secured to the lining of a well at any point necessary to permit the effective elevation of the water in the well.

The invention is hereinafter more fully described and claimed, and illustrated in the accompanying drawings, wherein:—

Figure 1 is a view partly in vertical section and partly in side elevation of a well pump constructed in accordance with the present invention;

Figure 2 is a sectional view on an enlarged scale taken on the vertical plane indicated by the line 2—2 of Figure 1;

Figure 3 is a sectional view on an enlarged scale taken on the vertical plane indicated by the line 3—3 of Figure 1;

Figure 4 is a sectional view taken on the horizontal plane indicated by the line 4—4 of Figure 3;

Figure 5 is a sectional view taken on the horizontal plane indicated by the line 5—5 of Figure 3;

Figure 6 is a sectional view taken on the horizontal plane indicated by the line 6—6 of Figure 2;

Figure 7 is a sectional view taken on the horizontal plane indicated by the line 7—7 of Figure 2;

Figure 8 is a view partly in vertical section and partly in side elevation of the lower portion of the pump, illustrating a modified form of the means for preventing the separation of the cylinder from the piston and a modified form of the means for securing the cup leather of the piston in place, and

Figure 9 is a detail sectional view of the upper end of the piston shown in Figure 8.

Referring in detail to the drawings, 1 designates the piston, 2 the cylinder, 3 the piston anchoring means and 4 the discharge line of the pump. The piston 1 which is supported in an immovable upright position in the well 5 by the anchoring means 3, is of hollow or tubular formation, and is provided at its lower end with external screw threads 6 and at its upper end with internal screw threads 7. The cylinder 2 slidably embraces the piston 1, and a fluid-tight connection between these parts is established by a cup leather 8 which is secured to the upper end of the piston and contacts with the inner wall of the cylinder. The upper end portion of the piston 1 is counter-bored, and the lateral wall of this counter-bore 9 is provided with the screw threads 7. A hollow coupling 10 has its lower end portion positioned in the counter-bore 9 and engaged with the screw threads 7. The coupling 10 is provided with an outer annular shoulder 11 between which and the upper end of the piston 1 is located the horizontal member of the cup leather 8, so as to permit the coupling to secure the cup leather to the piston.

106

The coupling 10 contacts with the inner side of the vertical member of the cup leather 8 to hold such member against the inner wall of the cylinder 2.

5 A guide rod 12 is secured at its lower end, as at 13, in the upper end of the coupling 10, and slidably passes through a spider 14 arranged within the cylinder 2 near the upper end of the latter. A nut 15 engaged with the upper end of the guide rod 12 and the spider 14, provides means adapted to limit the movement of the cylinder 2 in a direction permitting separation thereof from the piston 1.

10 The coupling 10 is fully open at its lower end and communicates at such end with the piston 1, and it is provided above the cup leather 8 with openings 16 through which the fluid passes from the piston into the cylinder 2.

15 An anchoring tube 17 which is located below and in axial alignment with the piston 1, is secured to the lower end of the piston by a hollow coupling tube 18 which is engaged with the screw threads 6 of the piston and threadedly engaged, as at 19, with the tube. A tubular valve seat 20 is secured, as at 21, within the coupling 18. A ball valve 22 cooperates with the upper end of the seat 20 to prevent downflow through the piston 1, coupling 18 and tube 17, and it is maintained in proper relation to the valve seat by a cage 23 which is secured, as at 24, to the valve seat. The lower end of the tube 17 is fully 20 open to provide an intake port 25 for the pump. The intake valve 22 is located between this port and the piston 1.

25 The cylinder 2 is secured to the lower end of the discharge line 4 by a coupling 26, and arranged in the coupling is a check valve 27 adapted to prevent downflow through the discharge line and the cylinder. The cylinder 2 is provided near its lower end with radial openings 28 which, when the cylinder 30 is in its uppermost position with respect to the piston 1, are located above the cup leather 8 so as to permit fluid to flow outwardly therethrough over the upper end of the piston and cup leather so as to prevent sediment and sand from accumulating on these parts. In all other positions of the cylinder 2 with respect to the piston 1, the openings 28 are located below the cup leather 8 and upper end of the piston.

35 The external diameter of the lower portion 17^a of the tube 17 is smaller than that of the upper portion 17^b of the tube, and the intermediate portion 17^c of the tube has a downwardly tapered outer surface, and the anchoring means 3 is associated with this conical portion of the tube. This means comprises a series of cylindrical segments 29 which are arranged in surrounding relation to the conical tube portion 17^c and which are secured to such portions for axial and radial movements

40 with respect thereto by dovetail lugs 30 carried by said tube portion and engaged in dovetail grooves 31 formed in the segments 29. The grooves 31 incline downwardly and inwardly with respect to the axis of the segments 29 in order to cause the segments to move outwardly during the downward movement and inwardly during the upward movement of the tube with respect to the segments. The upper ends of the grooves 31 are closed, as at 32, and such closed ends of the grooves 45 cooperate with the lugs 30 in limiting the downward movement of the segments 29 with respect to the conical tube portions 17^c while the prop is being lowered into or withdrawn from the well. The segments 29 contact with the inner surface of the lining 33 of the well 5, and are held by the combined weights of the piston 1, coupling 18 and tube 17 and the column of water therein in contact with the well lining under such pressure as to prevent them from moving upwardly or downwardly.

50 The pump is lowered into the well with the anchoring segments 29 in their lowermost position on the tube 17. The anchoring segments 29 are supported in this position by the lugs 30, and when in this position they are contracted and will not interfere with the lowering of the pump into the well. Immediately before the pump has been lowered to the desired extent into the well, the anchoring segments 29 are held against movement by a cable 34 which is secured to the anchoring elements 29 by cords 35. The further downward movement of the pump into the well will cause the conical tube portion 17^c to pass downwardly through the anchoring segments 29 with the result that the elements will be moved into engagement with the lining 33 of the well. When the anchoring segments 29 grip the well lining 33, the piston 1, coupling 18, and tube 17 are held against upward or downward movement and the discharge line 4 may be reciprocated without displacing these parts. After the piston 1, coupling 18 and tube 17 have been anchored in the well, the cable 34 is given a sharp pull to break the cords 35, and thereafter the cable is withdrawn from the well.

55 The upper end portion of the discharge line is slidably mounted in an ordinary pump standard 36, and it is reciprocated through the medium of a lever 37 pivotally supported, as at 38, from the pump standard. A water tight connection is established between the discharge line 4 and the pump standard by a backing gland 39. The discharge line 4 is provided in its upper end with a discharge port 40 which communicates with the pump standard 36 at a point above the packing gland 39 and the water discharged into the pump standard when the discharge line flows from the pump standard by way of a spout 41. A slightly modified form of the means for 60 preventing the separation of the cylinder 2

- from the piston 1 is shown in Figure 8. This form of this means consists of rods 42 extending downwardly from the lower end of the cylinder 2 and slidably passing through vertical openings 43 in the coupling 18, the rods being provided at their lower ends with nuts 44 which contact with the lower end of the coupling to limit the upward movement of the cylinder with respect to the piston. 5
- 10 When this form of the means for preventing the displacement of the cylinder 2 from the piston 1 is employed, the cup leather 8 is secured to the upper end of the piston by a hollow nut 45 which is screw threadedly engaged in the upper end of the piston and contacts with the horizontal and vertical members of the coupling element, the nut being hollow to permit the passage of the fluid from the piston to the cylinder. 15
- 20 From the foregoing description, taken in connection with the accompanying drawings, it will be understood that the piston 1 is anchored in the well and that the cylinder 2 and the discharge line 4 are reciprocated with respect to the piston through the medium of the lever 37. During the upstrokes of the cylinder 2 and the discharge line 4, the fluid is drawn into the cylinder 2, the water passing into the cylinder through the tube 17, coupling 18 and piston 1 and being held against downflow through these parts by the valve 22. During the down-strokes of the cylinder 2 and the discharge line 4, the water is raised in the cylinder and discharge line and flows from the latter into the pump standard 36, the water being held against downflow through these parts by the valve 27. 25
- 30 While I have described the principle of the invention, together with the structure which I now consider the preferred embodiment thereof, it is to be understood that the structure shown is merely illustrative and that such changes may be made, when desired, as fall within the scope of the invention as claimed. 35
- I claim:—
1. In a well pump, a tubular piston open at its upper and lower ends, a tube extending downwardly from the piston, means for anchoring the tube in the well, a check valve located in the tube, a cylinder slidably engaging the piston, the passages throughout the piston and tube constituting the sole inlet for the cylinder and the check valve preventing downward flow through the cylinder and piston, a washer on the upper end of the piston contacting with the cylinder, the cylinder being provided near its lower end with radial ports adapted to occupy a position above the upper end of the piston when the cylinder is in uppermost position with respect to the piston so as to permit water to flow outwardly therethrough over the upper end of the piston and washer, a hollow coupling secured to the upper end of the piston and securing the washer in place and holding it in contact with the cylinder, a spider carried by the cylinder in the upper end of the latter, and a rod secured to the coupling and passing through the spider and provided at its upper end with a head cooperating with the spider to limit the upward movement of the cylinder with respect to the piston. 40
2. In a well pump, a tubular piston open at its upper and lower ends, a tube extending downwardly from the piston, means for anchoring the tube in the well, a check valve located in the tube, a cylinder slidably engaging the piston, the passages throughout the piston and tube constituting the sole inlet for the cylinder and the check valve preventing downward flow through the cylinder and piston, a washer on the upper end of the piston contacting with the cylinder, the cylinder being provided near its lower end with radial ports adapted to occupy a position above the upper end of the piston when the cylinder is in uppermost position with respect to the piston so as to permit water to flow outwardly therethrough over the upper end of the piston and washer, a hollow coupling secured to the upper end of the piston and securing the washer in place and holding it in contact with the cylinder, a spider carried by the cylinder in the upper end of the latter, and a rod secured to the coupling and passing through the spider and provided at its upper end with a head cooperating with the spider to limit the upward movement of the cylinder with respect to the piston. 45
3. In a well pump, a tubular piston open at its upper and lower ends, a tube extending downwardly from the piston, means for anchoring the tube in the well, a check valve located in the tube, a cylinder slidably engaging the piston, the passages throughout the piston and tube constituting the sole inlet for the cylinder and the check valve preventing downward flow through the cylinder and piston, a washer on the upper end of the piston contacting with the cylinder, the cylinder being provided near its lower end with radial ports adapted to occupy a position above the upper end of the piston when the cylinder is in uppermost position with respect to the piston so as to permit water to flow outwardly therethrough over the upper end of the piston and washer, the tube being provided in the wall thereof with vertical openings, and rods secured to the lower end of the cylinder and passing through said openings and provided at their lower ends with heads cooperating with the lower end of the tube to limit the upward movement of the cylinder with respect to the piston. 50

In testimony whereof I hereunto affix my signature.

ARTHUR C. NELSON.
